LAMP HOLDER MOUNTED ON CONTINUOUS CONDUCTOR

Joseph F. O'Brien, Lebanon, John B. Cataldo, Annandale, and Kenneth E. Vroom, Summit, N. J., assignors to John B. Pierce Foundation, New York, N. Y., a corporation of New York

Application November 16, 1948, Serial No. 60,286

1 Claim. (Cl. 339—175)

1

This invention relates to surface wiring, and more particularly to a lamp holder or receptacle for connecting an electric light bulb in convenient position in circuit with the continuous conductors of an electrical conductor strip. The invention is especially useful in its application to temporary or semi-permanent interior lighting, to which use, however, it is not restricted.

Rearrangement of a room, or shifting of interior partitioning to alter the size or horizontal dimensions of a room, frequently requires relocation of electrical outlets in the room. In such case, permanent walls may be pierced, additional convenience outlets may be installed therein, and the walls may be refinished about such installations. Also new walls or partitions may be constructed with suitable wiring conduits therein, and built-in convenience outlets may be appropriately provided in such walls when they are erected. In place of such relatively expensive construction, it is often preferred to fasten surface wiring along a wall or ceiling in the form of a conductor strip and to fix thereto, on the same surface, receptacles for connection of electrical equipment in circuit with the conductors of the strip. Light, sly and efficient convenience outlets into which the blades of outlet plugs may be inserted have been developed in profusion. Accordingly, strip wiring has gained considerable favor for use with attachment plugs for the cords of floor lamps, table lamps, fans, heaters, toasters and like utility appliances. However, development of equally desirable electric light sockets for attachment immediately to strip wiring has not kept pace with that of plug-in receptacles.

We have now found it possible to provide a simple, light, safe receptacle for connecting an electric light bulb, or the like, in circuit with the continuous conductors of an electric conductor strip. The receptacle is of minimum size, is pleasing in appearance, and is easily fixed at once to the conductor strip and to the surface along which the strip is fastened. Furthermore, the receptacle completely encloses all portions of the strip from which insulation is removed for transfer of energy to contacts with the electric light bulb.

One form of the invention is shown in the accompanying drawings in which—

Fig. 1 illustrates a wall and a ceiling along both of which a continuous strip conductor extends, and on each of which a receptacle, constructed and arranged according to the invention, positions an electric light bulb in circuit with the continuous conductors of the strip;

2

Fig. 2 is a longitudinal elevation of one of the receptacles shown in Fig. 1 and a section of the conductor strip to which it is attached, all shown on an enlarged scale;

5 Fig. 3 is a top plan view of the receptacle and conductor strip section shown in Fig. 2;

Fig. 4 is a broken, fragmental perspective view, on an enlarged scale, illustrating the electrical connections between the light bulb and the conductors of the strip within the receptacle;

10 Fig. 5 is a cross-section taken on the line V—V of Fig. 2;

Fig. 6 illustrates the receptacle cover shown in Figs. 2 and 3 as viewed from beneath, with the 15 base and electrical parts removed;

Fig. 7 is a plan view of a section of the conductor strip and electrical connections, with the receptacle housing removed;

20 Fig. 8 is a plan view of one of the conductor clips and its attachment prong, shown in Fig. 7;

Fig. 9 is a cross-section taken on the line 25 IX—IX of Fig. 2, the section being shown on an enlarged scale; and

Fig. 10 is an end elevation of the left-hand contact clip and attachment prong shown in Fig. 9.

The drawings illustrate a wall 12 and an adjacent ceiling 13, along the inner surface of which a conductor strip 14 is fixed to convey electrical energy to convenient points thereon. Positioned 30 upon the wall 12 and connected to the conductor strip 14 is a receptacle or lamp holder 15, into which an electric light bulb 16 is screwed for energization by the strip conductors. An identical lamp holder 15 is positioned upon the ceiling 35 13 where it is connected to the conductor strip 14 in identical manner.

The conductor strip 14 is of well-known construction, comprising a strip of insulating material 17 in which parallel conductors 18 and 19 40 are embedded. Attachment to the supporting surfaces may be effected by screws, nails, or the like (not shown), passing through the strip between its conductors and into the wall or ceiling.

The receptacle or lamp holder 15 comprises a 45 cover 20 and a bottom 21 which enclose certain contact and electrical connector elements, whereby the lamp or electric light bulb 16 is connected in circuit between the continuous conductors 18 and 19 of the strip 14. The cover 20 and the bottom 21 of the lamp holder are fitted 50 closely together and are held in closed position, as by screws 22. See Figs. 2 and 5. So fitted, the cover and bottom embrace the insulation of the conductor strip 14 at the ends of the lamp 55 holder, and protect the strip and electrical con-

nections which they enclose. To this end, the cover 20 has pairs of end channels 23, 23 at each of its ends, which closely embrace a good part of the insulating material immediately surrounding the strip conductors 18 and 19. A tongue 24 formed at each end of the cover 20 between the end channels of each pair, as shown in Fig. 6, fits against the insulating material of the strip between its conductors, and improves the enclosure of the strip at the ends of the lamp holder.

Fixing screws 25, 25 project through holes 26, 26 in the cover 20, and through coaxial holes (not shown) in the bottom 21 to enter the wall 12 or the ceiling 13 and fix the lamp holder to its surface. The heads of the fixing screws bear upon plane surfaces 27, 27 provided by shallow recesses on the curved outer face adjacent each end of the top 20. In passing through the holes 26 in the cover and the corresponding coaxial holes in the bottom 21 to enter the wall or the ceiling and hold the lamp holder thereon, the fixing screws 25 also pass through the insulating material 17 of the strip between the continuous conductors 18 and 19 thereof. Thus, the fixing screws 25 also act to fix the position of the conductor strip 14 within the lamp holder 15 and to fix the conductor strip to the supporting surface. Within the cover and the bottom, between the fixing screws 25, the insulating material 17 is removed from the continuous conductors 18 and 19 of the strip to permit attachment of electrical contacts for connecting the strip conductors to the lamp 16.

In the embodiment illustrated, a conductor clip 28 of spring metal is positioned in contact with each of the bared strip conductors 18 and 19 within the lamp holder 15. The clips 28 closely embrace the bared conductors by virtue of their resiliency, and make electrical contacts therewith. Unitary wings 29, 29 are formed upon the conductor clips at each of their ends, and are so formed as to draw the clips more closely about the conductor as the wings enter and are pressed together by appropriately formed sockets 30 within the cover 20. See Figs. 5 and 6. Each clip is formed with an attachment prong 31 thereon which extends therefrom in the direction of the unitary wings 29, 29. It is through these prongs that electrical connection is made between the strip conductors 18 and 19 and the electric light bulb 16.

Positioned between the attachment prongs 31, and 31 of the two conductor clips 28 and 28, when they are in place upon the conductors 18 and 19, is a base of insulating material 32 upon which the more immediate electrical connections for the lamp or electric light bulb 16 are fixed. As here shown, the base 32 is a slab of insulating material which extends substantially completely across a central chamber 33 formed within the top 20, when the lamp holder is assembled. The base is provided with opposite notches 34, 34 through which the attachment prongs 31 and 31 extend.

A metallic contact member is fixed to the base 32 for electrical connection along the stem of the electric light bulb 16. As here shown, this metallic contact member is a metallic shell 35 for reception of the stem of the electric light bulb. The shell 35 is open-ended and substantially cylindrical in shape; and it is corrugated to form a helical thread into which the stem of the electric light bulb 16 may be screwed for electrical connection and positioning. The metallic shell 35 is fixed at one end to the base 32. As here

shown oppositely disposed flanges 36, 36 are formed integrally upon one end of the shell and are turned inwardly at right angles to the shell. The flanges 36, 36 are fixed to the base 32 to hold the shell in position. In the embodiment illustrated, rivets 37, 37 serve this purpose. A conductor bar 38 is fixed by the rivets 37, 37 in electrical contact with both flanges 36 and 36 of the metallic shell 35, and also to the base 32. The conductor bar 38 is forked for this purpose, its legs being positioned away from the axial center of the shell. The end of the conductor bar 38, which is distant from its connection with the flanges 36 and 36, is turned upwardly away from the surface of the base to which it is attached and is connected mechanically and electrically to the adjacent attachment prong 31, as by a screw 39. See Fig. 7. A second conductor bar 40 is fixed to the base centrally of the shell extending outwardly through it beyond the shell out of contact therewith. The shell 35 is cut away sufficiently adjacent the base, as at 41, to permit the second conductor bar 40 to extend beyond the shell without making contact therewith. Thus, the second conductor bar has one end positioned concentrically of the shell and extends across the base 32 in a direction opposite to that of the conductor bar 38, having its outer end turned upwardly and attached mechanically and electrically to the adjacent attachment prong 31, as by a screw 42. Accordingly, an electric light bulb, screwed into the shell 35, will make electrical contact by its axial end terminal with the inner end of the second conductor bar 40. A spring member 43 is preferably fixed in electrical contact with the inner end of the second conductor bar 40 to bear resiliently upon the axial terminal of the electric light bulb as the latter is screwed fully into the shell 35. When screwed fully into the shell, the electric light bulb will be connected in circuit between the conductors 18 and 19; to the conductor 18 through the shell 35, the conductor bar 38, the attachment prong 31 and the clip 28; to the conductor 19 on the other side through the second conductor bar 40, the attachment prong 31 and the clip 28.

It is preferred to position a cylindrical collar 44 of insulating material between the shell 35 and the upstanding ends of the conductor bars 38 and 40 which are connected to the attachment prongs 31, 31. Short-circuiting between the shell and the second conductor bar 40 and between the shell and the attachment prongs 31, 31 is thus completely prevented. Additional insulation may be provided within the lamp holder by a sheet of fiber 45 extending parallel to the base 32 between the base and the bared conductors 18 and 19. The fiber sheet 45 has openings therein through which the attachment prongs 31 extend, but otherwise shuts off all electrical connections from the strip conductors.

To position the parts here described within the space enclosed by the cover 20 and the bottom 21, the electrical connections are first attached to the base and to each other as described. A sufficient length of insulating material 17 being removed from the conductor strip 14 at the desired location of the lamp holder, the assembled electrical connections are then applied to the bare conductors 18 and 19 by slipping the conductor clips 28 over the conductors. Thereupon, the cover 20 is placed over the assembly which is pushed up into the cover. So positioned, the wings 29, 29 of each clip 28 cause the clips to grip the conductors more firmly and

the shell 35 extends outwardly through a circular opening 46 in the cover which gives access to the central chamber 33 therein. A shouldered bushing 47 of insulating material internally threaded to engage the corrugated threads of the shell 35 is thereupon screwed onto the projected end of the shell to hold the base, the electrical connections fixed thereto and the immediately adjacent portion of the conductor strip within the top. See Figs. 2 and 9. Next, the bottom 21 is fixed in place by means of the screws 22, 22. The unit is now completely assembled. It is here noted that the ends of the top 20 and the bottom 21 close about the insulation of the conductor strip 14 almost completely protecting the sections of the conductors 18 and 19 from which insulation has been removed for the electrical connections. The entire assembly may now be fixed in place by means of the fixing screws 25, 25, the conductor strip being thereby additionally fixed in place with respect to the lamp holder. The electric light bulb 16 may now be screwed into the shell 35 for connection in circuit between the continuous conductors 18 and 19 of the strip.

Although the invention has been described in connection with an electric light bulb, it will be obvious that this bulb or lamp may be replaced by known types of threaded plugs having slots therein for connection with usual forms of attachment plugs.

From the foregoing, it will be evident that the invention provides a simple, light, small and safe receptacle or lamp holder for connecting an electric light bulb or like threaded electrical appliance in circuit with the continuous conductors of an electrical conductor strip. The lamp holder is easily applied, and makes a neat and pleasing appearance.

The form of invention here disclosed and illustrated in the drawings is presented merely as an example of how the invention may be applied. Other forms, embodiments and applications of the invention coming within the proper scope of the appended claim will readily suggest themselves to those skilled in the electric wiring art.

We claim:

A lamp holder comprising a base of insulating material; a metallic shell fixed to one face of said base and extending substantially at right

angles therefrom, said shell being corrugated to form a helical thread therein for reception of the stem of an electric light bulb; a conductor bar fixed to said base in electrical contact with said shell extending outwardly of said base therefrom; a second conductor bar fixed to said base for contact with the axial end contact of the electric light bulb extending outwardly of said base in opposite direction to that of the first-named conductor bar; conductor clips for engaging each of two bared electrical conductors of an insulated conductor strip disposed adjacent said base; and an attachment prong formed on each of said clips, one of said attachment prongs being connected to each of said conductor bars; in combination with an arched cover of insulating material, having a circular opening therein through which said shell extends beyond said top; a bottom of insulating material closely fitting with said cover to inclose said base and the elements connected thereto and to surround closely the insulation of the conductor strip beyond the ends of said clips; and a threaded bushing of insulating material externally engaging the threads of said shell and bearing upon the outer surface of said cover to draw said shell, said base, and the elements connected to said base within said cover; whereby an electric light bulb screwed into said shell and in contact with said second conductor bar at the end of its stem will be connected in circuit between the conductors of the conductor strip.
